DRYING APPARATUS

Gustave Andre Vissac, Vancouver, British
Columbia, Canada

Application September 18, 1941, Serial No. 411,414

4 Claims. (Cl. 34—172)

This invention relates to improvements in vertical drying apparatus.

An object of the present invention is the provision of apparatus for drying granular materials, such as coal, phosphates, salts, sand or the like.

Another object is the provision of vertical drying apparatus including means for preventing the material to be dried therein from sticking or clogging in the apparatus.

Another object is the provision of vertical drying apparatus which is automatic in its operation.

A further object is the provision of a vertical dryer which may readily be adjusted to handle different types of material.

A still further object is the provision of apparatus of the type described adapted to prevent moist granular material from forming relatively large lumps and also to prevent any accumulation of the material from dropping directly downwardly therein.

With these and other objects in view, the present invention consists essentially of drying apparatus comprising a vertical casing, means for supplying wet granular material to the top of the casing, material supplied to the casing being adapted to cascade downwardly over the baffles, inclined baffles pivotally supported by the wall of the casing, the free end of each baffle being located over the next lower baffle, means for directing hot air upwardly around the baffles in the casing and means for removing dried material from the bottom of the casing, as more fully described in the following specification and illustrated in the accompanying drawings, in which

Figure 1 is a vertical section through the drying apparatus,

Figure 3 is an end elevation of said drying apparatus,

Figure 2 is a plan view thereof, and

Figure 4 is an enlarged detail of the mounting of one of the baffles.

Referring more particularly to the drawings, 10 is a vertical casing, preferably tall and rectangular in cross section. Wet granular material may be supplied to the top of this casing in any suitable manner, such as by means of a chute 11 communicating with said casing adjacent the top thereof and extending from a hopper 12 which preferably has a feeder 13 at its discharge outlet.

A plurality of inclined baffles 14 are pivotally supported by the wall of the casing 10 with the free end of each baffle located over the next lower baffle. These baffles are usually supported by different sides, and preferably opposed sides, of the casing so that each baffle is staggered in relation to and preferably is of such length that it overlaps each adjacent baffle of the other side.

The casing 10 is preferably formed with a tapered bottom 15 having a central outlet 16 there-

in and, if desired, a suitable feeder 17 may be located at the discharge outlet 16.

Hot air or gases from any suitable source (not shown) are supplied to the casing 10 adjacent the bottom thereof by a pipe 18 while said air or gas, after pushing upwardly around the baffles 14 in the casing, is removed from the top thereof through a pipe 20.

The feeders 13 and 17 are well known in the art and they consist of star wheels which are rotated in any suitable manner, such as by a motor 21 connected by belts or chains 22 and 23 to pulleys or sprockets 24 and 25 mounted on the shafts of the wheels 13 and 17, respectively.

As each baffle 14 is mounted in the same manner, only one will be described in detail. The baffle is pivotally mounted in such a manner that it is normally retained at a desired angle but when sufficient pressure is applied to its upper surface it is capable of swinging downwardly in accordance with the pressure and within certain limits. A very simple method of accomplishing this is to mount the baffle on a shaft 26 journaled in the walls of the casing 10 adjacent one side thereof. This shaft projects outwardly beyond one wall of the casing and a lever 27 is fixedly mounted thereon approximately midway between its ends. This lever normally lies in a substantially horizontal plane, at which time the baffle is lying at the desired angle.

Suitable means is provided for adjustably limiting the upward movement of the inner end 28 of the lever 27, such as a cable 30 extending downwardly from said end to a turnbuckle 31, which, in turn, is anchored to the side of the casing 10, at 32. Suitable means is provided for normally urging the baffle into its uppermost position within the limits of the cable 30. This means is preferably a weight 33 slidably mounted on the outer end 34 of the lever 27, which may be removably secured thereon in any adjusted position by a set screw 35.

Suitable means is provided for adjustably limiting the lowermost position to which the baffle may pivot. In the illustrated example, a set screw 36 is threaded in a bracket 37 mounted on the casing 10 in line with and above the outer end 34 of the lever 27. The lower end of this set screw is normally spaced above said outer end and when the baffle pivots downwardly a predetermined distance, the lever strikes the set screw to prevent any further downward movement.

If desired, the outer end of the pipe 20 may be connected to a dust collector 38 of any known construction, which is connected by a pipe 40 to a suction fan 41. This fan may be connected by a belt and pulleys to the motor 21.

In operation, the wet granular material is directed into the upper end of the casing 10 by the chute 11. This material drops on to the upper

baffle 14 and cascades over it and the remaining baffles to the bottom of the casing, whence it passes out through the discharge outlet 16. Hot air is directed into the lower end of the casing by the pipe 18. This air moves upwardly around the baffles through the descending material and out through the pipe 20. The suction fan draws this air through the dust collector 38 which removes any fine dust therefrom.

When any material is very damp or sticky and tends to accumulate on a baffle, its weight soon causes the baffle to tip downwardly at a steeper angle than its usual setting until the material spills off. As the baffles overlap each other, this material drops on to the next lower baffle instead of dropping to the bottom of the casing 10. In this way, the movement of the accumulated material is retarded sufficiently to cause it to be dried before leaving the casing. Furthermore, the accumulated material is broken up as it strikes the various baffles.

The normal setting of a baffle 14 is adjusted by lengthening or shortening the cable 36 by means of the turnbuckle 31, while the steepest angle to which the baffle may pivot is adjusted by raising or lowering the set screw 36. This set screw has a further purpose. When some of the material accumulates on the baffle, it pivots to a steeper angle and causes the outer end of the lever 27 sharply to strike the set screw. This tends to jar the material on the baffle, loosen, and to break it up. The weight 33 is adjusted on the outer end 34 of the lever to regulate the weight of material which may gather on the baffle before it begins its downward movement and the rate of this movement in accordance with the weight of the material.

The angle of each baffle, the limit of its downward movement and the weight of material necessary to cause such movement may be readily regulated to suit the condition and type of material to be dried. Once the apparatus is set, it is completely automatic and the baffles prevent any clogging or undue accumulation of material therein while, at the same time, preventing any small accumulation from dropping directly to the bottom thereof without being adequately dried.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:

1. Drying apparatus comprising a vertical casing, inclined baffles pivotally supported adjacent their upper ends at opposed sides of the casing with the free lower end of each baffle overlapping each adjacent baffle at the opposite side, means for resiliently retaining each baffle at a predetermined angle; each baffle including a shaft journaled in the sides of the casing, one end of said shaft projecting beyond the casing wall, a lever fixedly mounted on said shaft end approximately midway between its ends, one end of said lever lying substantially along side the baffle, means for limiting the upward movement of said end of the lever, and means for limiting the upward movement of the opposite end of the lever; means for supplying wet granular material to the top of the casing, material supplied to the casing

being adapted to cascade downwardly over the baffles, means for directing hot air upwardly around the baffles in the casing, and means for removing dried material from the bottom of the casing.

5. 2. Drying apparatus comprising a vertical casing, inclined baffles pivotally supported adjacent their upper ends at opposed sides of the casing with the free lower end of each baffle overlapping each adjacent baffle at the opposite side, means for resiliently retaining each baffle at a predetermined angle; each baffle including a shaft journaled in the sides of the casing, one end of said shaft projecting beyond the casing wall, a lever fixedly mounted on said shaft end approximately midway between its ends, one end of said lever lying substantially along side the baffle, means for limiting the upward movement of said end of the lever, and a weight mounted on the opposite end of said lever; means for supplying wet granular material to the top of the casing, material supplied to the casing being adapted to cascade downwardly over the baffles, means for directing hot air upwardly around the baffles in the casing, and means for removing dried material from the bottom of the casing.

3. Drying apparatus comprising a vertical casing, inclined baffles pivotally supported adjacent their upper ends at opposed sides of the casing with the free lower end of each baffle overlapping each adjacent baffle at the opposite side, means for resiliently retaining each baffle at a predetermined angle; each baffle including a shaft journaled in the sides of the casing, one end of said shaft projecting beyond the casing wall, a lever fixedly mounted on said shaft end approximately midway between its ends, one end of said lever lying substantially along side the baffle, means for limiting the upward movement of said end of the lever, and a weight slidably mounted on said opposite end; means for supplying wet granular material to the top of the casing, material supplied to the casing being adapted to cascade downwardly over the baffles, means for directing hot air upwardly around the baffles in the casing, and means for removing dried material from the bottom of the casing.

4. 4. Drying apparatus comprising a vertical casing, inclined baffles pivotally supported adjacent their upper ends at opposed sides of the casing with the free lower end of each baffle overlapping each adjacent baffle at the opposite side, means for resiliently retaining each baffle at a predetermined angle; each baffle including a shaft journaled in the sides of the casing, one end of said shaft projecting beyond the casing wall, a lever fixedly mounted on said shaft end approximately midway between its ends, one end of said lever lying substantially along side the baffle, means for adjustably limiting the upward movement of said end of the lever, means for adjustably limiting the upward movement of the opposite end of the lever, and a weight adjustably mounted on said opposite end; means for supplying wet granular material to the top of the casing, material supplied to the casing being adapted to cascade downwardly over the baffles, means for directing hot air upwardly around the baffles in the casing, and means for removing dried material from the bottom of the casing.
